UNITED STATES PATENT OFFICE.

CHARLES A. BACKSTROM, OF CRAFTON, PENNSYLVANIA, ASSIGNOR TO PITTSBURG
WATER HEATER COMPANY, OF PITTSBURGH, PENNSYLVANIA, A CORPORATION
OF NEW JERSEY.

WATER-HEATER.

1,217,133.

Specification of Letters Patent. Patented Feb. 27, 1917.

Application filed June 24, 1915. Serial No. 36,012.

To all whom it may concern:

Be it known that I, CHARLES A. BACKSTROM, a citizen of the United States, residing at Crafton, in the county of Allegheny 5 and State of Pennsylvania, have invented new and useful Improvements in Water-Heaters, of which the following is a specification.

The invention relates to the means for supporting the coils in a coil heater. It has for 10 its primary objects the provision of a cheap simple construction which will securely hold the coils against sagging and warping, and the provision of a construction of the character 15 specified in which the coils can be easily removed and replaced in the heater. One embodiment of the invention is illustrated in the accompanying drawing, wherein—

Figure 1 is a face view of the heater with 20 the front hinged section removed, Fig. 2 is a plan view of one of the supporting rings, and Fig. 3 is a vertical section through a portion of the rear side of the heater.

The water container consists of the series 25 of sets of double spiral coils 1, 2, and 3 of well known construction having the inlet 4 and the outlet 5. This container is carried in the casing 6 in the lower portion of which is the battery of gas burners 7. The front 30 half of the casing is not shown, such half being hinged in the usual way to the lugs 8 and 9.

Secured to the casing are the rings 10, 10, 35 10, preferably of cast iron, one of such rings being shown in plan view in Fig. 2. Each 40 of these rings is provided with a bottom ledge 11 upon which the central turn of the set of coils rests and is also provided with three downwardly and inwardly inclined 45 fingers 12, 13, and 14. The fingers serve to support the lower turns of each of the sets of coils. The rings themselves are detachably secured in position by means of stove 50 bolts 15 (Fig. 3), there being one bolt for each ring at the rear side thereof. The sides of each ring are supported by lugs 16 cast upon the inner surface of the casing 6, so that when the securing bolts are removed the rings can be removed from the casing by 55 sliding them to the front.

It will be seen that the foregoing arrangement prevents any sagging of the turns of the coils. The large central turns, most liable

to sag, are supported throughout a large portion of their length, and the fingers 12, 55 13, and 14 form a sufficient support for the smaller turns. The rings also prevent the sets of coils from twisting or warping with respect to each other. At the same time the construction is a simple and inexpensive one, 60 and the coils can be very easily assembled and disassembled. If desired, and in order to make the coils still more secure against warping, wires 17 can be passed through the slots 18 (Fig. 2) of the fingers 13 and 14 and 65 around any desired number of turns of the coils. Other advantages incident to the construction will be readily apparent to those skilled in the art.

I claim—

1. The combination with a casing and a water container comprising a vertical series of sets of double spiral coils, of a support for each of the sets comprising a ring secured to the casing and open on one side and engaging the lower side of the central turn of the coil.

2. The combination with a casing and a water container comprising a vertical series of sets of double spiral coils, of a support 80 for each of the sets comprising a ring secured to the casing and open on one side and engaging the lower side of the central turn of the coil, the said rings being provided with downwardly and inwardly inclined fingers for supporting the lower turns of the sets.

3. The combination with a casing and a water container comprising a vertical series of sets of double spiral coils, of a support for 90 each of the sets comprising a ring secured to the casing and open on one side and engaging the lower side of the central turn of the coil, and means for securing the coils against upward movement with respect to 95 the rings.

4. The combination with a casing and a water container comprising a vertical series of sets of double spiral coils, of a support for each of the sets comprising a ring secured 100 to the casing and open on one side and engaging the lower side of the central turn of the coil, the said rings being provided with downwardly and inwardly inclined fingers for supporting the lower turns of the sets, 105 and means between the fingers and coils for

securing the coils against upward movement with respect to the fingers.

5. The combination with a casing having lugs cast in pairs on its opposite sides and a water container comprising a vertical series of sets of double spiral coils, of a series of supports for the sets comprising rings open

at their fronts and fitting between the said pairs of lugs, and means for securing the rings against movement laterally from between the said pairs of lugs, the rings being formed to engage and support the larger turns of the said coils. 10

CHARLES A. BACKSTROM.
